UNITED STATES PATENT OFFICE.

WALTER EVERETT MOLINS, OF LONDON, ENGLAND.

CIGARETTE-PACKING MACHINE.

Application filed March 19, 1923. Serial No. 626,188.

To all whom it may concern:

Be it known that I, WALTER EVERETT MOLINS, a citizen of the United States of America, residing in London, England, have invented certain new and useful Improvements in Cigarette-Packing Machines, of which the following is a specification.

This invention relates to cigarette packing machines and has for its object to provide such machines with means for compressing a bunch of cigarettes in such a manner that they may be packed tightly and snugly into a wrapper or package without being damaged or distorted.

10 The invention is particularly but not exclusively applicable for use with cigarette packing and wrapping apparatus such as is described in the specifications of United States Letters Patent No. 1,188,193 and

20 1,468,246.

According to the invention, each bunch of cigarettes on its passage to the wrapping or like mechanism is passed into a compression box comprising opposite relatively movable sides and a rigid top and bottom, said box moving with the cigarettes.

The arrangement is such that as the cigarettes pass into the box, the sides move so as to compress the bunch. The advancing 30 or leading end of the box is shaped so as to enter the wrapping or like mechanism and to protect the cigarettes during the wrapping or like operation, and to assist the accurate operation of said mechanism.

35 To enable the invention to be fully understood it will now be described by reference to the accompanying drawings in which the invention is shewn as applied to a cigarette packing machine of the type shewn in the 40 United States specification No. 1,188,193 fitted with a wrapping apparatus of the type shewn in the co-pending application above referred to.

In the drawings:—

45 Fig. 1 is a plan view of the machine with the wrapping material feeding and cutting devices removed,

Fig. 2 is a section on line II—II, Fig. 1 the wrapping material feeding and cutting devices also being shown,

Fig. 3 is a part section on line III—III, Fig. 2,

Fig. 4 is a view of a detail,

Fig. 5 is a section on line V—V, Fig. 2,

Fig. 6 is a diagram illustrating the working of the apparatus,

Fig. 7 is a view of the wrapping portion of the machine shewing a wrapper in the course of folding,

Figs. 8 and 9 are views of details.

The machine is designed to operate on bunches of cigarettes in two superposed rows, one row being delivered to the machine bed 1 and the top row being swept off a bridge 30 by a sweeper 31.

60 The machine bed 1 is provided with a slot 2 in which conveyor plates 3 travel, the bunches being formed in front of the conveyor plates 3.

A transverse slot 4 is formed in the bed 70 for the passage of the wrapping material *a* and as shown in Fig. 2, the wrapping mechanism comprises a folding box 5, folders 6, a guard 7 and a knife 31'. The wrapping material *a* is drawn from a reel *b* by feed 75 rollers 6', 7' adapted to be rotated continuously and passes through guides 8 through the slot 4. The roller 6' is mounted on a spindle 20' having a bevel wheel 21' gearing with a bevel wheel 22' carried on a 80 vertical spindle 23'.

The wheel 22' is driven by a bevel wheel 24' carried on a spindle 25' mounted in the sleeve 17' and adapted to be continuously 85 driven by a gear wheel 26' in any suitable manner.

The advancing ends of the cigarettes meet the material *a* and carry it between the folders 6 in the box 5. At the instant when the cigarettes thus meet the strip *a* the latter is severed at a point just below the guides 8 by a knife 31' actuated in the following manner.

90 The blade 31' is mounted on a spindle 32' pivotally carried in a sleeve 33' which is 95 clamped upon the spindle 23' by an arm 34' secured by bolt 35', so that the sleeve is carried round as the spindle rotates. The spindle 32' has a coiled spring 36' on its lower end, one end of which is secured to the cap 37' screwed on the spindle, the other end being attached to the sleeve 33'. A fixed stop 38' is arranged in the path of the knife and the latter has a thickened portion 39' adapted to meet the stop. As 100 the spindle 23' continues to rotate, the stop 38' pressing on the portion 39' detains the knife, forcing it back until the portion 39' slips therefrom. During this operation the spring 36' has been compressed and on the 105 knife leaving the stop, the spring exerts its force and throws the knife rapidly 110

across the material *a*, severing it so rapidly that there is no appreciable variation in the continuous feed of the material.

Further description of the wrapping and cutting mechanism will be found in the specification of United States Patent No. 1,468,246, to which reference may be had.

The cigarettes are moved in bunches by the plates 3 through guides 9. In the machine illustrated the bottom row of each bunch of cigarettes contains one cigarette less than the top row. To compensate for this, the guides 9 are provided with filling strips 10 at their lower sides as shewn in Fig. 5.

The compressing apparatus consists of a box having a top plate 11 mounted on blocks 12, secured by clamps 13, said clamps being so arranged that they can be swung out of position to free the top plate. The blocks 12 are bevelled at one end so that the bevelled faces form a continuation of the inner surfaces of the guides 9.

The sides of the box are formed by compressor members 14 carried on links 15, 16. The inner faces of the members 14 may be shaped as shewn in Fig. 3 to avoid distortion of the outer cigarettes of a bunch and the conveyor plates 3 may also if desired, be shaped to conform to the shape of the members 14.

The links 15, 16 are pivoted to the members 14 by pins 17 at one end and at the other end, the links 15 are connected to bevelled pins 18 and the links 16 to spring pins 19, the pins 18, 19 being mounted in brackets 20 on the machine bed.

The brackets 20 also serve to carry a spindle 21, mounted transversely of the machine and having a cam 22 at its centre and four bevel segments 23 positioned as shewn in Fig. 1. The spindle 21 is rotated by suitable gearing from the main drive of the machine and each segment 23 is formed as shewn in Fig. 8.

These segments 23 are similar to an ordinary bevel wheel in appearance but are formed without teeth and with an interrupted conical surface.

A portion 27 of the conical surface is the actual working surface, the remaining surface 28 corresponding to the root cone of a bevel wheel and not being utilized for driving.

The heads of the bevel pins 18 (Fig. 9) are of similar construction except that a larger portion of the conical surface is utilized as a working surface.

One of the spring pins 19 is shewn in Fig. 4, the torsion spring 29 assisting the operation of the bevel gear during reverse movements of the links.

On the upper side of the top plate 11 a depresser plate 25 is pivoted between

two bearing brackets 24 for the purpose of 65 pressing the upper row of cigarettes into position after they have been swept off the bridge 30. The plate 25 is operated by cam 22 and the end of plate 11 is turned up at 11° to provide a stop for the plate. 70 A small spring-pressed flap 32 is pivoted in bearings on the plate 11 for levelling the ends of the top row of cigarettes in case they are in advance of the bottom row.

In machines in which the two rows of 75 cigarettes are brought together at some distance from the conveyor, the depresser plate 25 and flap 32 may be dispensed with if desired.

The face of the foil guard 7 of the wrapping mechanism is curved at 7° as shewn to give the foil a curve similar to that which it will take when folding commences and a guide 26 attached to plate 11 ensures that the foil enters the slot 4. 85

The operation of the above described apparatus is as follows:—

A bunch of cigarettes A is carried through the guides 9 by the conveyor plate 3 and reaches the position shewn in full lines Fig. 6. Immediately the links 15 start to move by reason of the working faces of the bevel segments 23 engaging the bevel pins 18 the compressing members 14 move inwards and also in the direction of motion of the cigarettes, the speed of the members in the direction B being equal to that of the cigarettes so that no rubbing action takes place. 95

The cigarettes are thus compressed and 100 after passing the point of maximum compression shewn by the dotted lines 50 (Fig. 6) the members 14 open out just enough to allow the cigarettes and conveyor piece 3 to pass along. This inward and outward 105 movement of each compressing member 14 is caused by the corresponding bevel pin 18 being alternately driven by its pair of bevelled segments 23. As spindle 21 rotates continuously in one direction, it will 110 be seen that one of the segments 23 rotates the bevel pin 18 until the working faces of the bevels disengage. The plate 14 remains stationary for a short time while the working faces of the pin and the first segment are disengaged and then the other segment engages the bevel pin on its other flank and rotates the pin in the opposite direction, causing the plate 14 to be returned to its original position. 115

The working conical surface of each bevel segment extends for 90° and each pair of segments is mounted so that the angular distance between their working surfaces is as indicated by the dotted lines Fig. 8. 120

The working conical surface of each pin 18 extends for 170° as shewn in Fig. 9. 125

The outlet from the compressing mem-

bers 14 may be a mouthpiece through which the bunch of cigarettes is passed into a packet, but as herein illustrated the cigarettes pass into a wrapping apparatus. The 5 leading ends of the members 14 enter the foil folding box (Fig. 7) and definitely mark the lines about which the foil folds, the folding operation being as described in United States Patent No. 1,468,246.

10 In Fig. 6 the members 14 are shewn in their final position by the chain lines C.

It will be understood that the action of the machine is continuous and that the sides of the compression box are moved to compress 15 each bunch of cigarettes in succession.

In some instances it may be desired to compress the cigarettes vertically as well as horizontally and mechanism may be provided to give a suitable motion to the top 20 plate of the compression box similar to that imparted to the sides.

Various constructional modifications may be made, for example the bevel drive of the side members of the box may be replaced by 25 cam mechanism or rocking arms.

Obviously the invention may be applied to cigarette packing machines of various types and to machines in which the cigarettes are introduced directly into a slide 30 or packet without being previously wrapped.

In the machine illustrated, to assist the accurate operation of the folding or wrapping mechanism the wrapping material may be passed through the creasing mechanism 35 described in the specification of co-pending application for United States Letters Patent Serial No. 626,187.

Having thus described the nature of the 40 said invention and the best means I know of carrying the same into practical effect, I claim:—

1. Apparatus for use in cigarette packing machines for compressing moving cigarettes comprising a box having movable sides mechanically operated to compress the cigarettes as they are carried through said box continuously, without interfering with the 45 continuous passage of the cigarettes.

2. Apparatus for use in cigarette packing 50 machines for compressing moving cigarettes comprising a box having movable sides automatically operated to move inwards to compress the cigarettes and outwards to release same and also to move in the same direction as the cigarettes.

3. Apparatus for use in cigarette packing 55 machines for compressing moving cigarettes comprising in combination, a machine bed, means for moving bundles of cigarettes along the machine bed continuously, a top plate 60 arranged above the bed, movable side plates cooperating with the top plate, to compress cigarettes and means for moving the side

plates inwards and outwards and in the same direction as the cigarettes. 65

4. Apparatus for use in cigarette packing machines for compressing moving cigarettes comprising in combination, a machine bed, means for moving bundles of cigarettes along the bed continuously, a top plate arranged above the bed, movable side plates 70 co-operating with the top plate to compress cigarettes, parallel links pivoted to the machine and to the side plates and means for operating the links to move the side plates. 75

5. Apparatus for use in cigarette packing machines for compressing moving cigarettes comprising in combination, a machine bed, means for moving bundles of cigarettes along the bed continuously, a top plate arranged above the bed, movable side plates 80 co-operating with the top plate to compress cigarettes, a pair of parallel links pivoted to the machine and to one side plate, a pair of parallel links pivoted to the machine and to the other side plate, bevelled pins on the links, a rotary spindle mounted transversely of the bed and bevel segments on the spindle 85 co-operating with the bevelled pins on the links. 90

6. Apparatus for use in cigarette packing machines for compressing moving cigarettes comprising in combination, a machine bed, means for moving bundles of cigarettes along the machine bed continuously, means 95 for wrapping said bundles, means for feeding wrapping material, a top plate arranged above the bed, movable side plates co-operating with the top plate to compress the cigarettes, means for moving the side plates 100 inwards and outwards and in the same direction as the cigarettes, a folder box for receiving the cigarettes after compression, and shaped ends on the movable side plates adapted to enter the folder to assist in folding 105 wrapping material around the cigarettes.

7. Apparatus for use in cigarette packing machines for compressing moving cigarettes comprising in combination, a machine bed, means for moving bundles of cigarettes 110 along the machine bed continuously, a top plate arranged above the bed, movable side plates cooperating with the top plate to compress cigarettes, means for moving the side plates inwards and outwards and in the same 115 direction as the cigarettes a folder box for receiving the cigarettes after compression, means for feeding a wrapping strip across the path of the cigarettes between the folder box and the movable side plates and shaped 120 ends on the movable side plates adapted to enter the folder box to assist in folding the wrapping material around the cigarettes.

In testimony whereof I have signed my name to this specification.

WALTER EVERETT MOLINS,
